US00D987556S

(12) **United States Design Patent** (10) **Patent No.:** **US D987,556 S**
(45) **Date of Patent:** **** May 30, 2023**

(54) **POWER STATION**

(71) Applicant: **Guangdong Marshell Electric Vehicle CO., LTD**, Guangdong (CN)

(72) Inventor: **Zhonghua Dong**, Guangdong (CN)

(73) Assignee: **Guangdong Marshell Electric Vehicle CO., LTD**, Zhaoqing (CN)

(**) Term: **15 Years**

(21) Appl. No.: **29/753,064**

(22) Filed: **Sep. 29, 2020**

(51) **LOC (14) Cl.** **13-02**

(52) **U.S. Cl.**

USPC **D13/103**; D13/107

(58) **Field of Classification Search**

USPC D13/103, 106, 107, 108, 109, 110, 112, D13/116, 118, 119, 184, 199; D15/199

CPC F02N 11/12; F02B 63/04; H02J 7/0045

(57) **CLAIM**

The ornamental design for a power station, as shown and described.

DESCRIPTION

FIG. 1 is a top, front, right side perspective view of a power station showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawing depict portions of the power station that form no part of the claimed design.
